UNITED STATES PATENT OFFICE.

FRANK D. POWELL, OF CHICAGO, ILLINOIS, ASSIGNOR, BY MESNE ASSIGNMENTS, TO ACME CARD SYSTEM COMPANY, OF CHICAGO, ILLINOIS, A CORPORATION OF ILLINOIS.

INDEXING SYSTEM.

Application filed October 30, 1922. Serial No. 597,714.

To all whom it may concern:

Be it known that I, FRANK D. POWELL, a citizen of the United States, residing in the city of Chicago, county of Cook, and State of Illinois, have invented certain new and useful Improvements in Indexing Systems, of which the following is a specification.

This invention relates to improvements in indexing systems and refers more particularly to an improved type of hanger or card-holder by means of which a plurality of cards may be carried on a single holder or hanger.

Among the objects of the invention are to provide a card-holder which will permit a large number of cards to be held by a single frame by mounting a plurality of cards on each hanger in overlapping relation. A further object is to supply a holder whereby tab-cut cards are supported in a pocketed carrier; to provide a locking means whereby the cards are fixedly held in place.

Fig. 1 is a face view of the holder with two cards in position.

Fig. 2 is a perspective view showing the upper card and its card-carrier in a raised position.

Fig. 3 is a view of the card-holder with the cards removed. Fig. 4 is a detail of the locking device.

Referring to the drawings, the card-holder consists of a supporting stay or strip 1 which may be of any suitable flexible material, the ends of which protrude slightly beyond the edges of the card, and are adapted to be held by the flanges of the card-frame, not shown. The width of the strip serves to hold the card-holder and overlapping cards in regular spaced apart relation. Over the strip which is preferably of wood, card board, fibre board or like material, is glued or otherwise fastened a fabric strip 2, to which is glued the lower hanger or card-carrier 3 which may be of a relatively tough paper such as manila or paper board of a like stock. Fabric is used for the hinged portion at the top, as the repeated folding of the paper would soon crease and tear the paper used as the card-holding portion 3.

The card carrier 3 is slit centrally to form two card-carriers and each carrier has along its lower edge a pocket reinforcement

4 or 5 which is fastened to the card by means of metal staples 6 both at the ends and at the rear of the carrier, as shown at 7 in Fig. 3. The cards used in connection with this type of construction are of the usual type as shown at 8 but instead of the straight lower edged cards usually used with visible equipment, the cards are tab-cut so that the lower edge of both cards is visible when the hangers or carriers are positioned in overlapping relation upon the frame.

In order to hold the cards rigidly in position, one of the upper corners of each of the carriers is slit in a three-sided figure as shown at 9 so that when the lower or tab-cut edge of the card is inserted in the lower pocket, the upper corner may be put through the slotted portion thereby holding it closely against the card. To remove the card, it is only necessary to bend the card centrally and remove the upper corner from the locking slit and withdraw the lower edge from the pocket.

This type of construction permits a greater number of cards being mounted in a single frame, and is one from which the cards may be easily removed and inserted; also by tab-cutting the cards as explained, the lower edge upon which the identifying matter is placed, is at all times visible as in the usual type of visible index system.

The holders are light in construction and easily removable and replaced in the equipment frames, affording an attractive design of visible card index equipment.

At the top of the card as shown in Fig. 4 is the notch 10, by means of which the card is held against sidewise movement in a horizontal direction by engaging the slit 9 in the holder 3. This locking feature serves to rigidly hold the card in position in the holder, which card would otherwise have a tendency to sag, if it was held merely by its corner.

The card holders having protective pocket members, carry individual cards. The pocket carriers extend only partially across the lower edge of the supported card. An advantage of the construction is the fact that one half of the reverse sides of the cards is available for recording purposes without removing the cards from their holders.

I claim as my invention:

1. A card holder for visible indexing sys-

tems consisting of a flexible strip insertable between the lateral flanges of a frame, a fabric hinge portion fastened to the strip, a plurality of card-carriers fastened to said hinge portion, a pocket reinforcement on each carrier adapted to support a card, and an interlocking means for holding the card against the carrier.

2. Card holders for visible indexing systems consisting of flexible strips insertable between the lateral flanges of a card frame, a flexible hanger attached to each of the strips, a plurality of flexible carriers attached to each hanger, transparent pockets attached to the lower edge of each carrier adapted to support the cards, and a locking slit in the carriers for supporting the cards rigidly in position.

3. Card holders for visible indexing systems consisting of flexible strips insertable between the lateral flanges of a card frame, flexible hinged elements attached to the strips, a plurality of pocketed card-carriers attached to portions of each of the flexible hinged elements, locking means on the carriers adapted to hold the cards in position, tab-cut index cards adapted to be inserted in the pockets and held by the locking means in an overlapping position, whereby identifying matter on the tab portions of the respective cards is at all times visible.

4. Card holders for visible indexing sys-

tems comprising support members, card-carriers hinged thereto and having card-supporting pockets extending partially 35 across the lower edges of the cards.

5. Card holders for visible indexing systems comprising support members, card-carriers hinged thereto and having transparent protective card-supporting pockets 40 extending partially across the lower edges of the cards.

6. Card holders for visible indexing systems comprising support members, card-carriers hinged thereto and having card-supporting pockets extending partially 45 across the lower edges of the cards, and locking means engaging a corner of the cards assisting in holding them in a horizontal position.

7. Card holders for visible indexing systems consisting of a plurality of card-supporting members attached to a single hanger and index cards carried therein, said card-supporting pockets extending partially 55 across the lower edges of the cards.

8. Card holders for visible indexing systems consisting of a plurality of card-supporting members attached to a single hanger and having transparent protective card-supporting pockets exposing the indexed portion of the respective cards supported therein.

FRANK D. POWELL.
